HYDRAULIC POWER SHOVEL

William W. Sloane, Chicago, Ill., assignor, by
mesne assignments, to Lima Locomotive Works,
Incorporated, Lima, Ohio, a corporation of
Virginia

Application September 25, 1931, Serial No. 565,015

3 Claims. (Cl. 214—135)

This invention relates to material handling machines such as power shovels, cranes and the like, and more particularly to machines of the character described wherein certain of the parts are hydraulically actuated and controlled. The principal object of the invention is to provide an improved hydraulic operating system including a continuously operating pump, wherein means are provided for automatically unloading the pressure in the system during periods when the main hydraulic actuating devices are not in operation.

15 A further object is to provide means for supplying pressures of differing values for different purposes, a higher pressure for the main hydraulic actuating devices, and a lower pressure for the hydraulic controlling devices such as clutch and brake operating plungers.

20 The invention may best be understood by reference to the accompanying drawings, in which Figure 1 is a view in side elevation of a power shovel constructed in accordance with my invention.

shovel constructed in accordance with my invention.

Figure 3 is a diagram showing the main parts of the hydraulic system forming a part of my invention.

30 Figure 4 is a detail sectional view of a low pressure hydraulic plunger suitable for operating certain control devices such as clutches and brakes.

Figure 5 is an enlarged detail section of the unloading valve.

35 Referring now to details of the embodiment
of my invention illustrated in the drawings, the
novel features are shown as applied to a power
shovel having a prime mover and the main oper-
ating parts carried on a frame or turn table 1.
40 pivotally mounted to swing in a horizontal plane
on a base 2, said base being provided with suit-
able propelling mechanism such as an endless
tread mechanism 3. The shovel 4 is of the dip-
per type having a handle 5 provided with a rack
45 6 engaging a pinion 7 driven through gears 7^a
and pinion 7^b on shaft 7^c of a hydraulic motor
9 mounted on the boom 8. The dipper 4 is fur-
ther connected for operation by means of a single
cable 16 passing over a sheave 17 on the outer
50 end of boom 8 and wound on a main operating
drum 18.

The boom is arranged as usual at the front end of the platform so as to be raised or lowered by suitable draft means, herein comprising a cable 10 wound about sheaves 11 and 12 carried on

the end of the boom and on a frame support 13, respectively, and having one end wound on drum 15 on the platform. Power actuating and controlling means for said drum is provided in any suitable manner.

The driving motor 20 is of the usual multi-cylinder hydrocarbon type mounted on a transverse axis at the rear of the platform. The main drive shaft 21 of the motor is connected through a pinion 19 and gear 22 to a jack shaft 23 in front of the motor. This shaft is arranged to drive a hydraulic pump 25 of any suitable form, the pump herein shown being of the reciprocating type having three radially disposed cylinders, and provided with an outlet 25^a and inlet 25^b. 15

The shaft 23 also has operative connections for driving the main power drum 18 through pinion 26, gear 27 on shaft 28, gear 29 on shaft 30, and a clutch 31, at the opposite end of said shaft, affording selective driving engagement between said shaft and drum 18 normally mounted loosely 20

thereon. Operative connections are also afforded for driving the endless tread device 3 on the truck 2, herein consisting of a gear 35, operatively connected to the shaft 23 through gears 29, 27, 25 and loosely mounted on shaft 36. Reversible

22, and loosely mounted on shaft 35. Reversible power connections are mounted on the shaft 36 herein consisting of a sliding clutch member 37, adapted to be connected with a pair of oppositely connected gears 38 and 39 adapted to drive bevel

connected gears 36 and 35, adapted to drive bevelled gear 40 in opposite direction. Said bevelled gear is mounted on the upper end of a vertically disposed shaft 41 concentric with the axis of movement of the turntable or main frame 1.

Suitable drive connections are afforded between the shaft 41 and the endless tread 3 on the truck. As will be seen in Figure 2 the endless tread device may be driven in either direction by shaft clutch member 37 to engage either beveled gears 38 and 39 with shaft 36. A clutch member 48 is mounted on the end of clutch 37 to engage and disengage shaft 36 from drive gear 35 thereon, at will.

Referring now to the hydraulic actuating and control devices which are utilized in connection with the parts above described, the main hydraulic pump 25 has an outlet or high pressure pipe 50 and an inlet or supply pipe 51 leading from a storage or low pressure tank 52. A low pressure pipe 53 is connected to the storage tank 52. A safety valve 54 is preferably connected between the high and low pressure lines, as is best indicated in the diagram, Figure 3. A pressure tank or dome 64 partially filled with air is preferably connected in the high pressure line 50.

Means for providing the crowding motion to the dipper handle comprises the hydraulic motor 9, similar in construction to the hydraulic pump 25, but now used as a motor, and connected between the high and low pressure lines 50 and 53 by pipes 9^a and 9^b through swivel joints 60 and 61 disposed on the horizontal axis of the hinged boom 8, and from thence through pipes 62 and 63, respectively, the former of which is connected to valve 9^c of any suitable form for controlling the pressure to the motor 9.

A similar motor 65 is provided for swinging the turntable 1 on its base 2, said motor being connected across the high and low pressure lines 50 and 53 and controlled by valve 68. This valve is preferably reversible and may be of the well-known rotatable four-way type, with reversing pipe lines 66 and 67 between the motor and valve, and a waste pipe 65^b leading to the low pressure line 53. The shaft 65^a of motor 65 drives a pinion 70 meshed with gear 71 loosely mounted on shaft 28, and having a bevel gear 72 carried therewith, driving a bevel gear 73 on upright shaft 74. Said upright shaft has a pinion 74^a meshed with a circular rack 74^b on the base, as seen in Figure 1. This swinging movement may be in either direction because of the reversibility of motor 65 as described.

Referring now to the means for automatically unloading the pressure in the system during periods when the main operating motors 9 and 65 are not in operation, the unloading system is best illustrated in the diagram in Figure 3. A cross line 75 affords connection between the high pressure line 50 and the low pressure line 53, communication through said cross line being controlled through a manually operated valve 76 and an automatic pressure responsive valve 77.

The valve 76 is held in open position by spring 76^b to permit unloading of the system, excepting when it is desired to use the full pressure available for the main operating motors 9 and 65. Accordingly an interlocking connection is provided between the valves 9^c of the motor 9 and the valve 68 of motor 65, so that when either of said valves is open, the master valve 76 will be closed. In the form shown, this interlocking connection consists of a rocker arm 99 adapted to engage the upper end of the valve stem 76^a of valve 76, and having a rod 100 connected to its upper end, which rod carries a plurality of stops 101, 101 selectively engageable by cams 102, 103 carried on the valve handles of each of the valves 9^c and 68. The arrangement is such that as soon as either of the valves 9^c or 68 is in open position, the cam 102 or 103 will engage the respective stops 101 so as to move the master valve 76 into closed position. At all other times, when pressure is not being used for the main operating motors 9 and 65, the valve 76 is maintained in open position to permit unloading of the system, as will now be described.

Details of the unloading valve are shown in Figure 5. Said valve consists of a casing 78 having three cylindrical chambers 79, 80 and 81, forming parts of valve members A, B and C, connected by a cross passage 82 at adjacent ends of said chambers. The two outside chambers 79 and 81 of valve members A and C have restricted valve ports 79^a and 81^a closed by valve stems 79^b and 81^b, respectively. The valve stem 79^b is normally held open by compression spring 83, while the valve stem 81^b is held closed by compression spring 84, the spring 83 being slightly weaker than the spring 84. The central valve chamber

80 of valve B has an intermediate poppet valve member 85 on stem 86. A piston 87 at the upper end of said stem is reciprocably mounted in the upper end of the cylinder 80 with its upper face open to the passage 82 so as to be responsive to pressure therein. The valve 85 is normally held closed by spring 88.

When the valve 76 in cross line 75 is open, pressure from the pump is communicated to each one of the three valve cylinders 79, 80 and 81 as follows: The pipe 75 communicates with the lower end of cylinder 80 below valve 85, and also communicates with a branch pipe 91 through a one way check valve 92. Said branch pipe 91 communicates with the upper end of the cylinder 81 and also through an extended line 93 to the lower end of cylinder 79. A pipe 94 branches off the connecting pipe 91 to a pressure tank 95, hereinafter referred to as the intermediate pressure tank, the purpose of which will hereinafter more fully appear.

A discharge passage 96 is formed in the valve casing 78 and communicates with the valve chamber 79 above the piston 79^c of valve stem 79^b through port 96^a, while a similar port 96^b extends in the opposite direction and communicates with the adjacent valve cylinder 80 between the valve 85 and the piston 87 therein. The discharge passage 96 communicates with pipe 96^c leading direct to the low pressure line 53. A passage 97 communicates between the valve chamber 80 between valve 85 and piston 87 and the adjacent valve chamber 81 below the piston 81^c of valve stem 81^b.

As has already been suggested, the master valve 76 controlling the unloading cross line 75 is normally held open by spring 76^a. When the main operating motors 9 and 65 are not in use and the pump 25 is being operated, pressure builds up in the high pressure line 50 and communicates through valve 76, pipe 75, the one-way check valve 92 and branch pipes 90 and 91 to the lower end of valve cylinder 79 and the upper end of valve cylinder 81. Pressure is also communicated through the one-way check valve 92 to the lower end of valve cylinder 80, but the valve is normally held in closed position by spring 88.

As will be seen in Figure 5, the valve stem 79^b is normally open while valve stem 81^b is normally closed. As pressure builds up in the valve chamber 79, the spring 83 being slightly weaker than the spring 84 closes valve A; a slight increase in pressure on valve C then opens the latter, admitting the pressure to the upper chamber 82 where it is effective upon the piston 87 so as to open the valve 85. This permits the fluid to flow through the valve 85 and unload through passage 96^b and outlet passage 96 to pipe 96^c direct to the low pressure line 53.

The critical pressure at which the unloading takes place is maintained in the intermediate pressure tank 95. In the event that the master valve 76 is closed so as to shut off pressure from the cross line, pressure may be maintained in the intermediate tank by the automatic shutting off the unloading valve system as follows:

As soon as pressure lowers to the critical point, valve C will close and valve A will open, releasing the pressure from the upper cylinder 82 and piston 87 communicating therewith. The spring 83 in the valve B will then close valve 85, thereby discontinuing any further escape of fluid to the low pressure line and diverting any additional flow into the intermediate pressure tank until

such time as the critical pressure is restored. The check valve 92 prevents any return flow through line 75.

I find it practical and desirable to fix the critical pressure of the unloading system at a value much less than the working pressures available for the main operating motors 9 and 65. For instance, in a power shovel of the character described, the usual working pressure for said main operating motors may be approximately 1000 pounds per square inch, while the critical pressure for operating the unloading valve may be in the neighborhood of 200 pounds per square inch. With the working pressure as thus indicated, it will be understood that the intermediate pressure tank and associated lines will normally be subject to a much lower pressure than that maintained in the high pressure line.

I utilize this reduced pressure available in the intermediate pressure tank for the operation of auxiliary control devices such as means for shifting the clutches and setting the brakes of the power shovel. As shown in Figure 2 and the diagram of Figure 3, a low pressure pipe line 105 is connected to the intermediate pressure tank 95, and branch lines 106 and 107 lead to a clutch operating valve 106^a and a brake operating valve 107^a, respectively. Said clutch and brake operating devices 106^a and 107^a associated with valves 106 and 107, are of the usual reversible plunger type shown in detail in Figure 4. A similar low pressure operating device 108 may be also used for tripping the dipper latch, as indicated in Figures 1 and 2.

Since the clutch and brake operating devices require far less energy than the main operating motors 9 and 65, the pipe lines supplying said devices may be much smaller than those of the high pressure lines. Furthermore, the pressure in the intermediate tank will be maintained fairly constant regardless of excessive fluctuations in the high pressure lines during operation of the main operating motors 9 or 65. Although the working pressure in the intermediate pressure tank 95 will be reduced slightly from time to time by use of the auxiliary control devices, yet the pressure will be intermittently restored to its maximum each time the unloading system is operated during the frequent periods of inoperation of the main operating motors 9 and 65.

Although I have illustrated and described one particular embodiment of my invention, it will be understood that I do not wish to be limited to the exact construction shown and described, but that

various changes and modifications may be made without departing from the spirit and scope of my invention.

I claim:

1. In a machine of the character described, a prime mover, a hydraulic pump driven by said prime mover, a high pressure line, a low pressure line, hydraulic power devices connected between said high and low pressure lines, a by-pass line connected between said high and low pressure lines and having a pressure-responsive valve therein, a pressure tank connected to said high pressure line, and a pipe leading from said tank to said pressure-responsive valve and supplying pressure to open the latter when the pressure in said tank exceeds a predetermined value, and other hydraulic power devices connected between said pressure tank and said low pressure lines.

2. In a machine of the character described, a prime mover, a hydraulic pump driven by said prime mover, a high pressure line, a low pressure line, hydraulic power devices connected between said high and low pressure lines, a by-pass line connected between said high and low pressure lines and having a manually operable valve and a pressure-responsive valve therein, a pressure tank connected to the line between said valves and a pipe leading from said tank to said pressure-responsive valve adapted to supply pressure to open the latter at a predetermined pressure in said tank, and other hydraulic power devices connected between said pressure tank and said low pressure line.

3. In a power shovel, a frame, a boom, a dipper thereon including a reciprocably movable handle and thrust mechanism therefor, a cable drum on said frame having flexible cable connections with said dipper, a constant speed engine on said frame having optional driving connection with said cable drum, a hydraulic pump driven by said engine, a high pressure line and a low pressure line, a hydraulic motor for said thrust mechanism between said high and low pressure lines, a by-pass line between said latter lines having a manually controlled valve and a pressure-responsive valve therein, a pressure tank connected to said by-pass line between said valves, a pipe leading from said tank to said pressure-responsive valve adapted to supply pressure to open the latter at a predetermined pressure in said tank, and hydraulic control means for said cable drum connected between said pressure tank and said low pressure line.

WILLIAM W. SLOANE.
